Primary Examiner — Paula Allen Greene(74) *Attorney, Agent, or Firm* — Westman, Champlin & Koehler, P.A.(57) **CLAIM**

The ornamental design for a headset, as shown and described.

DESCRIPTION

FIG. 1 is a front right perspective view of a headset showing our new design;

FIG. 2 is front elevation view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines depict portions of the headset that form no part of the claimed design.

1 Claim, 5 Drawing Sheets(56)
